UNITED STATES PATENT OFFICE.

FREDERICK B. PRANTE, OF HUMPTULIPS, WASHINGTON. ASSIGNOR OF ONE-HALF TO
MICHAEL SPINNER, OF GATE, WASHINGTON.

DOOR-SECURER.

1,150,621.

Specification of Letters Patent. Patented Aug. 17, 1915.

Application filed November 11, 1914. Serial No. 871,565.

To all whom it may concern:

Be it known that I, FREDERICK B. PRANTE, a citizen of the United States, residing at Humptulips, in the county of Chehalis and 5 State of Washington, have invented certain new and useful Improvements in Door-Securers; and I do hereby declare the following to be a full, clear, and exact description of the invention, such as will enable others 10 skilled in the art to which it appertains to make and use the same.

This invention relates to new and useful 15 improvements in door securers, and has for its principal object to provide a novel form of securer which may be easily and quickly applied or removed from a door.

Another object of the invention is to provide a securer which will effectively hold 20 the door against movement from the outside.

Still another object of the invention is to provide a novel device which may be easily 25 and cheaply constructed from sheet metal, thereby rendering the same inexpensive to manufacture.

With these and other objects in view, the 30 invention consists in the novel combination and arrangement of parts which will be fully set forth in the following specification and accompanying drawings, in which,

Figure 1 is a horizontal sectional view 35 through a door and door jamb illustrating this device in position, Fig. 2 is an end view in elevation of the invention showing the same applied to a fragment of a door and jamb, Fig. 3 is a side view in elevation of the invention, and Fig. 4 is a detail perspective view of the locking slide.

Referring now to the drawings by characters of reference, the numeral 1 designates a door of the usual construction which 40 coöperates with the door jamb 2. This door jamb is provided with the usual bead 3, which bead is nailed or otherwise secured thereto.

The attachment, which is designated generally by the numeral 4 and shown in position on the door, is formed of the body 5 having one end turned angularly as at 6. 45 This body is provided with the diagonal slot 7 having extending parallel therewith the slot 8, one wall of which is provided with a plurality of ratchet teeth 9 which are formed for an obvious purpose. The slot 8 is of 50 considerably less length than the slot 7 and

is designed so that the slide, which is best illustrated in Fig. 4, may be easily manipulated. This slide is designated generally by the numeral 10 and comprises the body 11 having formed at one end the enlargement 12, which enlargement is bent angularly and extends along one of the lateral edges of the body. An extension 13 is formed on the opposite edge at a point spaced inwardly from the end of the body on which the enlargement 12 is formed, and this extension 14 is bent angularly as at 15 so that this portion extends parallel with the enlargement 12. The free terminal of the extension 14 is bent upwardly as at 15 and lies in a plane parallel with the body 11. A reduced threaded extension 16 is formed at the end of the body 11 opposite the enlargement 12, and this extension 16 is arranged intermediate the side walls of the body and 75 extends at such an angle that when the slide is in position on the body, this extension lies at right angles to the face thereof. A suitable thumb screw 18 is arranged to coöperate with the threaded extension 16 80 in holding the device in its adjusted position.

It will be apparent from the foregoing that in use the securer is placed in position in a door in the manner illustrated in Fig. 85 1 so that the flange 6 is forced into the space between the bead 3 and the jamb 2 when the door is closed. The slide 10 is then slid forwardly so that the enlargement 12 engages the door and the extension 16 90 engages in the spaces in the notches, thus holding the slide against movement. It will be clearly seen that when the device is in this position the door is held against movement and cannot be opened until the slide 95 is released and pulled back to permit the enlargement 12 to enter the slot 8, thereby allowing the device to swing inwardly and out of engagement with the door.

While in the foregoing there has been 1 shown and described the preferred embodiment of this invention, it is to be understood that such changes may be made in the combination and arrangement of parts as will fall within the spirit and scope of the invention as defined in the appended claims.

What is claimed is:

1. A door securer comprising a body, said body being formed with a pair of parallel slots, teeth formed on the body and 1

- projecting into one of the slots, a door-engaging slide, guides on the slide slidable within the slots, and means carried by said slide to engage the teeth and hold the slide in adjusted position.
2. A door securer including a body, said body having a pair of diagonal slots therein, teeth formed on the body and projecting into one of the slots, a slide, said slide having guides on opposite sides thereof, said guides adapted to be slidable within the slots, screw means at one end of the slide to engage the teeth of the slot and hold the same in an adjusted position.
3. A door securer comprising a body, an angular extension at one end of the body, said body being provided with a pair of parallel diagonal slots, teeth formed on the body and projecting into one of said slots, a slide, a door engaging element formed on the slide, and a thumb screw secured on the opposite terminal of the slide, said thumb
- screw being arranged to engage the teeth to hold the slide in an adjusted position.
4. A door securer comprising an elongated body, an angular extension at one end of the body, said body being provided with a pair of diagonal slots, said slots being extended in directions toward the opposite corners of the body, teeth formed on the body and extending into one of the slots, and a door securing slide, said slide having guides formed on opposite sides thereof, said guides being slidable within the slots, means carried by said slides arranged to engage the teeth to hold the slide in an adjusted position in the slots.

In testimony whereof I affix my signature in presence of two witnesses.

FREDERICK B. PRANTE.
